UNITED STATES PATENT OFFICE.

EDWARD LANE, OF PITTSBURGH, PENNSYLVANIA.

SMOKE-CONSUMING FURNACE.

1,162,736.

Specification of Letters Patent. Patented Nov. 30, 1915.

Original application filed October 4, 1909, Serial No. 520,786. Divided and this application filed January 3, 1910. Serial No. 535,953.

To all whom it may concern:

Be it known that I, EDWARD LANE, a citizen of the United States, residing at Pittsburgh, in the county of Allegheny and State of Pennsylvania, have invented certain new and useful Improvements in Smoke-Consuming Furnaces, of which the following is a specification.

This is a division of my prior application, 10 Serial No. 520,786, filed October 4, 1909.

My invention relates to furnaces of that kind in which means are provided for supplying heated air through the bridge wall to the burning fuel on the grate in front of 15 said wall.

Generally stated, the object of my present invention, as herein shown and described and claimed, is to provide a novel and improved construction tending to solve many of the 20 problems involved in the supplying of heated air to the burning fuel in this particular manner.

More specifically considered, the object of my invention is to provide a simple and improved arrangement of the pipes by which the air is heated and supplied to the bridge wall, and of the means for supporting the outer or intake ends of said pipes; and also to provide an efficient and improved construction of the bridge wall; and in addition 30 it is also an object to provide certain details and features of construction and combinations tending to increase the general efficiency and serviceability of a furnace having air heating and supplying means of this particular character.

To these and other useful ends, as will hereinafter more fully appear, and as will be apparent to those skilled in the art, my 40 invention consists in matters hereinafter set forth and claimed, and shown in the accompanying drawings, in which—

Figure 1, is a central vertical longitudinal section of the rear portion of a boiler furnace embodying my invention. Fig. 2, 45 is a vertical transverse section of the furnace to disclose the front end of that part of the structure shown by Fig. 1. Fig. 3, is a horizontal section taken on the line III—III of Fig. 2. Fig. 4, is a sectional perspective view to disclose more clearly the bridge-wall construction. Fig. 5, is a detail perspective view of one of the sleeves for receiving the rear end of one of a series of the air-feeding pipes. Fig. 6, is an enlarged view of

the rear end of the furnace to disclose the construction and arrangement of the corresponding end of one of the sleeves and the pipe therein. Fig. 7, is a section on the line VII—VII of Fig. 6 and includes a 60 valve-controlled plug, not shown in the last-named figure. Fig. 8, is a central vertical section of a modified construction of the bridge-wall of the furnace. Fig. 9, is a section on the line IX—IX of Fig. 8. Fig. 65 10, is a vertical section on a reduced scale, of a second modified form of the bridge-wall, and also shows one of the pipes for supplying air thereto, equipped with an enlargement or collar to seal the hole in the 70 bridge-wall through which said pipe extends, when the pipe is elongated by expansion.

In the said drawings, 1 indicates the side walls, 2 the rear wall and 3 the boiler of 75 the furnace.

4 indicates the bridge-wall and 5 a portion of the grate dividing the chamber in front of the bridge-wall into an upper or combustion chamber 6, and a lower chamber 80 80 or ash pit 7.

The bridge-wall is preferably formed as shown, to overhang the rear part of the ash pit, and forming a support for the overhanging portion of the bridge-wall and the rear end of the grate, is an angle bar 8. The bridge-wall is also formed with a vertical column of bricks 9 and at opposite sides of said column, with inclined bricks 10 sloping downward and forward and forming the lower part of 85 the mouth of a transverse hot-air chamber 11 in the bridge-wall, the rear wall of said chamber being formed by a casting 12 extending from side wall to side wall and having enlarged triangular upwardly-projecting extensions 13 (see Fig. 4) embedded at their side edges in the side walls of the furnace. The top of the mouth of chamber 11 is 90 preferably in the form of a cross-bar 14 and parallels the bricks 10, and said cross-bar 14 is provided with depending ribs 15, which taper from their lower outer corners which rest upon the outermost of the bricks 10 forming the bottom of the mouth of chamber 11, toward the column 9, at which point 100 they merge into the bottom of bar 14. (See Fig. 4). By this arrangement it will be seen that, what may be termed, the throat of the mouth grows narrower from column 9 to 105 the side walls of the furnace and thus tends 110

to discharge the greater volume of hot air from chamber 11 into the middle portion of the furnace.

16 indicates triangular plates secured at their outer edges in the side walls and stepped at their lower edges upon the rear edge of the bar 14 forming the top of the mouth of the chamber 11, said triangular plates 16 paralleling the triangular extensions 13 of casting 12 and being spaced forward thereof, and projecting rearwardly from the upper or hypotenuse edges of plates 16, are flanges 17 which fit at their rear edges in grooves 18 in said extensions 13 and thus form the top of the enlarged ends of chamber 11. A plate 19 bridges the space between the lower ends of flanges 17 and the upper edges of the central portions of cross bar 14 and casting 12 to form the top of the central or smaller portion of said chamber 11, it being noticed in Fig. 4, that the casting 12 is preferably in two sections, one only being shown, adapted to be step-jointed and bolted together and that said sections are supported upon the rear portion of the bridge wall, it being also understood in this connection that by reason of the fact that the chamber 11 is larger at its ends than at its middle as hereinbefore suggested, but that as its throat near the middle is of greater area than at its ends, the tendency of the hot air in the ends of said chamber is to be forced toward its center and pass, under pressure, through the throat and mouth into the central portion of the furnace and thus tend to act as a blast on the fuel on the grate and effect a combustion sufficiently fierce to consume the smoke and combustible gases or products of combustion which arise from the coking fuel on the grate.

To protect the preferably metal portions of the bridge-wall from the intense heat of the furnace, bricks 20 are superposed upon plate 19 and flanges 17 of plates 16, and bricks 21 paralleling bricks 10 are secured upon and project forward from bar 14 to increase the length of the upper part of the mouth of chamber 11, as shown in full lines 50 Fig. 1, and dotted lines Fig. 4.

To supply hot-air to the chamber 11 where its temperature will be raised preliminary to its forcible ejection onto the fuel as hereinbefore explained, I provide two inclined series of air pipes 22. Each series of said pipes collectively slope downward and laterally inward and individually slope downward and forward and said pipes communicate at their front ends with the enlargements of chamber 11 and at their rear ends extend through sleeves 23 in the rear wall of the furnace, the pipes being supported at their intermediate points by brick or equivalent piers 24. The sleeves 23 are slit at their 65 ends at 25 to produce lips 26 which are bent

upwardly and bear against the outer and inner faces of said rear wall. The rear ends of pipes 22 project slightly beyond the rear ends of the sleeves and are slit to produce lips 27 bent outwardly against the rear ends of the sleeves to guard against any possibility of the pipes sliding forward. After the parts are thus arranged the rear ends of the spaces between the pipes and sleeves are plugged with clay 28, or its equivalent, to prevent air passing into the furnace through the rear wall except through pipes 22, which clay can be readily dislodged should it be found necessary to withdraw one of the pipes 22 from position 80 and replace it by another. Fitting in the rear end of such pipe 22 is a tubular plug 29 provided with a pivoted valve or closure plate 30 so that the pipes may be separately wholly or partially closed.

Referring now to Figs. 8 and 9, it will be seen that the rear portion of the bridge-wall is extended upward and then forward to the back of the casting 12 as shown at 31 so as to provide an auxiliary hot air chamber 32, and said chamber is provided at its lower end with a mouth 33 through which hot air may pass forwardly into the furnace below the grate. To supply air to chamber 32 for the purpose of maintaining combustion of fuel, such as clinkers, a series of pipes 34 communicate at their front ends with chamber 32, the rear ends of said pipes being adapted to be secured in the rear wall of the furnace in any suitable manner but preferably as explained in connection with the rear ends of pipes 22, though the replacement of pipes 34 will not be necessary as frequently as the replacement of pipes 22 because the latter are in the more direct path of the flames which pass up over the bridge-wall and under the boiler to the rear end of the same.

To intensify the combustion in the combustion chamber a blast of hot air, which enters from the rear end of the furnace, is heated by pipes 22 and is discharged over the grate 5, through the downwardly and forwardly inclined mouth of chamber 11, and in this connection it should be stated that the mouth of said passage is above the plane of any fuel that may accumulate upon the grate and therefore cannot be clogged or closed by such fuel, the forward inclination of the mouth guarding against any possibility of fuel remaining in it that might possibly be projected therein by a sufficiently powerful thrust of the poker or other device against the fuel.

It will also be apparent that a fierce combustion can be maintained in the extreme rear of the furnace because of the fact that the hot air of chamber 11 is discharged down upon the grate. It will also be observed by reference particularly to Figs. 1 125 130

and 2, that the construction and arrangement of the upper part of the bridge wall and of the series of air supply pipes 22 is such as to provide a passage which tapers 5 substantially uniformly from the bridge wall to the rear end of the boiler, such passage being of substantially inverted-arc shape so as to correspond approximately to the curvature of the lower side of the boiler in order that the lower part of the latter shall be as effectively subjected to the action of the flames as the side portions. The arrangement of the pipes 22 is such that any one of them may be quickly and easily 10 removed at any time without the removal or disturbance of a brick, as the sleeves 23 are of sufficient length to permit said pipes to be readily centered with respect to the holes provided for their reception in the rear part 15 of the bridge wall.

In the modified constructions shown in Figs. 8 to 10 inclusive, air is heated in pipes 34 and additionally heated in chamber 32 and is discharged forwardly into the ash pit, 20 below grate 5, part of such air passing upwardly through and forwardly over the grate and coöperating with the blast of air from the mouth of chamber 11 to effect complete consumption of the fuel upon said 25 grate 5, it being also understood that the clinkers on the grate and in the ash pit are kept alive for a time by the air which passes forwardly from chamber 32 to effect the extraction of all of the heat units and thus 30 tend to the economical operation of the furnace as a whole. As pipes 34 are elongated by expansion the collars 35 approach and close the openings through which the pipes extend into chamber 32. In Fig. 10, recess 32 is formed by an inclosure 36, which may 35 be of any suitable material; whereas, in Fig. 8, this recess is formed by the brick work or masonry 31, in the manner previously described. In any case, however, the recess 32 coöperates with the previously described mouth in the bridge wall to promote combustion by supplying heated air to the fuel on the grate.

I do not limit myself to the exact construction shown and described.

Having thus described the invention what I claim as new and desire to secure by Letters-Patent, is;

1. A furnace provided with a boiler, a 55 grate underlying the boiler, a bridge wall also underlying the boiler at the rear end of the grate and provided with a chamber having an inclined mouth to discharge air downward and forward upon the fuel on the grate, sleeves extending downwardly and forwardly through the rear wall of the furnace and provided at their opposite ends with outwardly projecting lips engaging the inner and outer faces of said wall, pipes extending through said sleeves and communi-

cating at their front ends with the said chamber of the bridge wall, and means to prevent forward slippage or movement of said pipes.

2. A furnace provided with a boiler, a 70 grate underlying the boiler, a bridge wall also underlying the boiler at the rear end of the grate and provided with a chamber having an inclined mouth to discharge air downward and forward upon the fuel on the 75 grate, sleeves extending downwardly and forwardly through the rear wall of the furnace and provided at their opposite ends with outwardly projecting lips engaging the inner and outer faces of said wall, pipes extending through said sleeves and communicating at their front ends with the said chamber of the bridge wall, and lugs projecting laterally outward from the rear ends of said pipes engaging the rear ends of said 80 sleeves to prevent forward movement or creepage of the former.

3. A furnace provided with a boiler, a grate underlying the boiler, a bridge wall also underlying the boiler at the rear end 90 of the grate and provided with a chamber having an inclined mouth to discharge air downward and forward upon the fuel on the grate, and a throat which expands inwardly from its opposite sides toward its 95 middle to concentrate the major portion of the volume of air centrally of the mouth, and two series of pipes extending through the rear wall of the furnace and communicating at their front ends with the chamber 100 of the bridge wall near its opposite ends.

4. A furnace provided with a boiler, a grate underlying the boiler, a bridge wall also underlying the boiler at the rear end of the grate and provided with a chamber 105 having an inclined mouth to discharge air downward and forward upon the fuel on the grate; and a throat which expands inward from its opposite sides toward its middle to concentrate the major portion of the volume of air centrally of the mouth, and two series of pipes extending through the rear wall of the furnace and communicating at their front ends with the chamber 110 of the bridge wall near its opposite ends, the pipes of each series collectively sloping downward and inward and individually downward and forward.

5. A furnace provided with a boiler, a 120 grate underlying the boiler, a bridge wall also underlying the boiler at the rear end of the grate and provided with a transverse chamber of greater cubical capacity at its ends than at its middle; said chamber having a downwardly and forwardly sloping mouth, said mouth extending straight across from one side of the grate to the other, and two series of pipes extending transversely of the bridge wall, communicating at their front ends with the enlarged ends 125 130

of the chamber and with the atmosphere at their rear ends.

6. A furnace provided with a boiler, a grate underlying the boiler, a bridge wall also underlying the boiler at the rear end of the grate and provided with a transverse chamber of greater cubical capacity at its ends than at its middle, said chamber having a downwardly and forwardly sloping mouth, and a throat which expands inwardly from each end to direct the major portion of the volume of air through the central portion of said mouth, and two series of pipes communicating at their front ends with the enlarged ends of the chamber and with the atmosphere at their rear ends.

7. In a furnace, a bridge wall provided with a chamber therein, air pipes disposed back of said bridge wall, said pipes being exposed to the heat of combustion and arranged to supply heated air to said chamber, and means at the other ends of said pipes for regulating or controlling the influx of free air, said pipes being dependent for such influx upon the draft of the furnace, said pipes being arranged in two separated groups, one group at each side of the furnace, the top of each group sloping downward and inward, each pipe being straight from end to end, and the bridge wall being higher at each side than in the center thereof.

8. In a furnace, a bridge wall provided with a chamber therein, air pipes disposed back of said bridge wall, said pipes being exposed to the heat of combustion and arranged to supply heated air to said chamber, and means at the other ends of said pipes for regulating or controlling the influx of free air, said pipes being dependent for such influx upon the draft of the furnace, said chamber having a mouth for delivering the heated air downward upon the burning fuel, and a throat governing the delivery of air from said chamber to the

said mouth, which throat is highest at the middle and low at the ends thereof.

9. A furnace provided with a boiler, a grate underlying the boiler, a bridge wall also underlying the boiler at the rear end of the grate and provided with a chamber having an inclined mouth to discharge air downward and forward upon the fuel on the grate, and a throat which expands inwardly from its opposite sides toward its middle to concentrate the major portion of the volume of air centrally of the mouth, and two series of pipes extending through the rear wall of the furnace and communicating at their front ends with the chamber of the bridge wall near its opposite ends, said chamber having a plate forming a back wall for supporting the ends of said pipes, a recess behind said plate to discharge heated air below the grate, and air heating pipes leading to said recess from the atmosphere.

10. A furnace provided with a boiler, a grate underlying the boiler, a bridge wall also underlying the boiler at the rear end of the grate and provided with a transverse chamber of greater cubical capacity at its ends than at its middle; said chamber having a downwardly and forwardly sloping mouth, said mouth extending straight across from one side of the grate to the other, and two series of pipes extending transversely of the bridge wall, communicating at their front ends with the enlarged ends of the chamber and with the atmosphere at their rear ends, said chamber having a plate forming a back wall for supporting the ends of said pipes, a recess behind said plate to discharge heated air below the grate, and air heating pipes leading to said recess from the atmosphere.

In testimony whereof I affix my signature, in the presence of two witnesses.

EDWARD LANE.
